UNITED STATES PATENT OFFICE.

NORRIS ELMORE CLARK, OF PLAINVILLE, CONNECTICUT, ASSIGNOR TO ROBERT S.
ALLYN, TRUSTEE, OF NEW YORK, N. Y.

EXPANDED-METAL MACHINE.

1,314,507.

Specification of Letters Patent. Patented Sept. 2, 1919.

Application filed April 28, 1917. Serial No. 165,081.

To all whom it may concern:

Be it known that I, NORRIS ELMORE CLARK, a citizen of the United States of America, residing at Plainville, Connecticut, have invented a new and useful Expanded-Metal Machine, of which the following is a specification.

My invention relates particularly to mechanism for slitting stock which is to be subsequently expanded either in the same or separate machine.

My Patents #1,146,554 and #1,224,523 show and describe mechanism of this general character. It is my main object to improve these constructions so as to permit of long high speed operation, facilitate construction and replacement of parts and permit adjustment of guides for the stock to correspond with the height of the cutters.

In the preferred form the guides for the stock are especially constructed so as to be vertically adjustable and articulated so that the entrance end may remain at substantially the fixed height of the in-feeding rolls and the parts adjacent the cutters may be vertically adjusted up and down to correspond with the height of the die cutters. Lifters and strippers are movable with the punch and die cutters so as to grip the stock adjacent the cutting edges and prevent it from drawing over and wearing the edges of the cutters. Each individual cutter is held positively to its holder by a single screw and forced into its seat by a separate screw. The marginal and interior unslotted strips of the stock as it leaves the slitting tools may be guided along upwardly curved guides and the intermediate unslotted strips may be carried down between these guides so as to corrugate the stock and open the meshwork.

Figure 1, is a longitudinal, vertical, sectional view of mechanism embodying the improvements of my invention showing the parts in their relative positions for action but with the punch member raised higher than it would be in actual practice and the expanding member disconnected from the punch member.

Fig. 2, is a similar transverse sectional view, some parts being omitted and some broken away.

Fig. 3, is a plan view of the die member with parts of the guides broken away, and some parts omitted.

Fig. 4, is a view of the under side of the punch member showing parts broken away, and some parts omitted.

Fig. 5, shows an enlarged plan of die units and a horizontal section of the coacting punch unit.

Fig. 6, is a vertical longitudinal section of the die unit of Fig. 5.

The die holder 10 is adapted to be secured in any suitable manner to the bed of any suitable type of press having an automatically reciprocating gate which carries the punch holder 11.

The punches and dies as herein shown are in the form of wedge-shaped cutter units such as 12 and 13. Each cutter has its cutting edges formed so as to produce the desired lengths of slits and bonds for instance, such as set forth in my Patent #1,146,554. The cutting edges may be flat or slightly sheared if desired. The die holder is provided with a series of seats such as 14 for the die cutters and the punch holder is provided with a series of seats such as 15 for the punch cutters. The cutters are clamped to their respective holders by screws such as 16 and 17 and each cutter is forced into its seat by screws such as 18 and 19. Figs. 5 and 6 show wedge blocks 12^a and 13^a with the cutting edges on separate plates 12' and 13' and the up-keep cost of this is less than with one-piece cutters. Packing plates such as 12^b may be employed if desired.

A V-shaped stripper or lifter 20 is located between adjacent die cutters beneath the punch cutter so as to hold the stock against the edges of the punch cutter and prevent it from drawing in between the cutting edges. This lifter 20 has two ears 21 at one end and an ear 22 at the other end, which ears extend beyond the opposite ends of the coacting die cutters. The ear 22 carries a rod 23 which is adapted to be screwed up or down so as to adjust the height of its lower end. The lower end rests on a rod 24 which is pressed upward by a spring 25 and screw 26. Each ear 21 carries a rod 27 which is also vertically adjustable and rests on a rod 28 which is pressed upward by a spring 29 and screw 30. The upper end of each rod 28 fits in a bushing 31 which fits snugly in the opening 32 at the end of the corresponding cutter seat 14. These lifting strippers are thus guided between the adjacent die cutters and serve not only to hold

the stock while it is being cut, but to lift the stock from between the cutters after the cutting stroke.

The punch cutters are also preferably provided with spring pressed stripping and holding means, in this case shown to be a single plate 35 having openings 36 to allow for the punch cutters 13. This stripper plate 35 may be guided and connected to the punch member 11 by a number of screws such as 37 and pressed downward by a number of springs such as 38. To keep the tools in good working order it is desirable that the edges of the strippers 20 adjacent the die cutters and the edges of the stripper 35 adjacent the punch cutters be kept smooth and hard. Obviously individual upper gripping strippers may be used between the punch cutters as between the die cutters, or the lower gripping lifters 20 may be connected as in the case of the upper member 35.

For accuracy of work and long life of the cutters when operating at high speed it is desirable that the punch and die members be accurately guided in their vertical movement and for that purpose I provide a pillar-post 40 at each corner of the die holder which fits in a vertical hole 41 in a corresponding corner of the punch holder. These pillar-posts prevent any lateral or torsional displacement of the holders even though the gate of the press may fit somewhat loosely in its guides. These pillar-posts also make it possible to assemble and adjust the tools on the bench.

The press carrying these tools should be provided with a suitable feeding mechanism such as a pair of rolls 45 driven intermittently by a suitable form of ratchet or worm. The length of feed will be adjusted so as to give the desired width of strand as set forth in my Patents #1,146,554 and #1,224,523. These feed rolls are usually arranged at a fixed height and the tools are of course varied in height as they are ground down or new ones substituted. It is accordingly desirable to have some form of vertically adjustable guides for carrying the stock from the feed rolls to the upper faces of the die cutters. I have accordingly provided a guide construction which can be removed and assembled and adjusted as a unit. The end members 46 have flanges 47 fitting in the slotted ends 48 of the die holders. These end members 46 are adapted to be clamped at the ends of the die holders by bolts 49. The end members are connected by a cross plate 50 secured to the flanges 51 below the level of the stock at the in-feeding side. A cover plate 52 is secured to the end members 46 for instance by screws or bolts 53. This cover plate has an opening to allow for the punch cutters and strippers. The vertical space between the plates 50 and

52 is just sufficient to allow for the greatest thickness of the stock which it is desired to handle. These plates 50 and 52 are adapted to be adjusted up and down with the end members 46 to correspond with the height 70 of the die cutters.

To connect up the feed rolls 45 with the guide plates 50 and 52 I provide an intermediate guide member as shown in Figs. 1 and 3. Each end member 54 is hinged at 75 55 on a bracket 56 which is vertically adjustable and adapted to be clamped by a bolt 57 passing through a vertical slot 58. The end members 54 are connected by a lower cross plate 59 and by an upper cross 80 plate 60 with a space beneath the top plate 60 sufficiently deep to accommodate the greatest gage of stock which it is intended to handle. By adjusting the bracket 56 up and down and tilting the end members 54 and cross plates 85 59 and 60, the guides may be so adjusted as to take the stock directly from the feed rolls 45 and deliver it between the guide plates 50 and 52.

To facilitate guiding the stock and holding it during the slitting and guiding it away from the tools it is desirable to form shallow beads at the edges. For this purpose feed rolls 45 may be provided with grooves 45' and beads 45''. The end piece 95 54 will be provided with a corresponding bead 54' and the cover guide plate 60 will be provided with a corresponding groove 60'. The end member 46 will be provided with a corresponding bead 46' and the cover 100 guide plate 52 a corresponding groove 52'.

As the stock leaves the slitting tools it may be expanded after the method set forth in my Patent #1,224,523. To provide greater uniformity in expansion however 105 the broad unslotted bands of the stock should be carried along curved guides 63, 63'. The broad strips should also be provided with cover guides 64, 64'. The intermediate narrow unslotted strips of the stock should be directed along another curved plane so as to bend the mesh-work uniformly and gradually without buckling. This may be accomplished by the curved expanding guide members 65 arranged between the adjacent 110 curved broad strip guides. These members 65 may be pivoted at 66 and operated by one or more links 67 connected to the gate or the punch member 11 so that as the punch member reciprocates the expanding guide 115 member 65 swings up and down and thus gradually and progressively opens the mesh-work. The marginal and interior broad strip guide members may be mounted so as to be vertically adjustable as at 68 so as 120 to correspond with the height of the die cutters. As the expanding members 65 are connected to the reciprocating member they are initially adjusted with the adjustment 125 of the punch holder.

What I claim is:—

1. In a slitting machine, a series of die cutters arranged in a row transversely of the machine, a guide member vertically adjustable with respect to the cutting faces of said die cutters, said guide member comprising a guide plate extending transversely and upper and lower bead guide sections and an introductory guide vertically adjustable and hinged on a horizontal axis and punch cutters coacting with the die cutters.

2. In a slitting machine, a series of die cutters, lifters arranged between the die cutters, vertically adjustable upper and lower guides at opposite sides provided with interfitting beads and grooves, a pair of introductory feed rolls and a vertically adjustable tilting introductory guide between the feed rolls and the cutters.

3. As an article of manufacture, a stripper for a slitting machine, comprising a V-shaped body portion and three guide pins carried thereby, one of said guide pins being located at the point of the V and the other pins being located at the opposite ends thereof.

4. In a slitting mechanism, a holder having a plurality of seats with tapered sides arranged spaced apart from each other transversely of the holder, a cutter block mounted in each seat and a single clamp screw for each cutter block passing through the holder at right angles thereto and screwed into the approximate center of the cutter block and a forcing screw for each cutter block, each forcing screw passing through the holder substantially parallel to the cutting face of the cutter block and pressing the cutter against the tapered sides of its seat.

5. Slitting mechanism including a holder, wedge-shaped cutters carried thereby and a vertically movable V-shaped member arranged between adjacent cutters adapted to coact with the punch cutter to hold the stock adjacent the edges of the cutters, the ends of the V-shaped member projecting longitudinally beyond the ends of the cutters, a rod carried by each end of the V-shaped member, guides for said rods in said holder and springs for said rods.

6. Slitting mechanism including a holder, wedge-shaped cutters carried thereby and a vertically movable V-shaped member arranged between adjacent cutters adapted to coact with the punch cutters to hold the stock adjacent the edges of the cutters, the ends of the V-shaped member projecting longitudinally beyond the ends of the cutters, a rod carried by each end of the V-shaped member, guides for said rods in said holder, springs for said rods and means for adjusting said rods for effecting the height of said V-shaped member relative to said cutters.

7. As an article of manufacture, a stripper for a slitting machine, comprising a V-shaped body portion and three guide pins carried thereby, one of said guide pins being located at the point of the V and the other pins being located at the opposite ends thereof, said pins being adjustably mounted in said body portion.

8. Slitting mechanism including a die holder having vertically slotted portions at opposite sides, removable cutters carried by said holder, a guide member having lateral projections vertically adjustable in the slotted portions of said holder, said guide member having lower and upper plates for guiding the stock to the cutters.

9. Slitting mechanism including a die holder, cutters carried thereby, a vertically adjustable guide member having upper and lower plates arranged to guide the stock to said cutters, a pair of feed rolls and a tilting guide between said feed rolls and said guide member.

10. Slitting mechanism including punch and die holders, cutters carried thereby, means for guiding the stock substantially on a level with the cutting faces of the die cutters, and a vertically adjustable tilting guide leading to said guiding means.

11. Slitting mechanism including a die holder, cutters carried thereby, a guide member for the stock substantially on a level with the cutting faces of said cutters, oppositely disposed vertically adjustable members carried by said holder, hinged end members carried by said vertically adjustable members and upper and lower guide plates carried by said end members.

12. Slitting mechanism including a die holder, cutters carried thereby arranged with their cutting edges in zig-zag line transversely of the holder, vertically adjustable members at opposite sides of said holder having longitudinally extending beads, cover plates having longitudinally extending grooves above said beads and feed rolls having grooved and beaded portions in line with said beads.

13. Slitting mechanism including a die holder, cutters carried thereby and having their cutting edges arranged in zig-zag line across the holder, a vertically adjustable guide member including beaded and grooved portions at opposite sides of said holders, a pair of beaded and grooved feed rolls and an angularly adjustable guide member between said feed rolls and said vertically adjustable guide member.

14. Slitting mechanism including a holder, having a plurality of seats spaced apart transversely of the holder and each having converging side walls, a cutter unit secured on each seat between the side walls, each comprising two plates oppositely inclined relative to the direction of feed and each

- 41
- having a plurality of cutting edges, a wedge-shaped block fitting between said plates, a forcing member acting against the base of said block and a clamping member directly securing said block to said holders.
15. Slitting mechanism including upper and lower pairs of cutters arranged with the cutting edges of each pair inclined toward each other in the direction of feed of the stock, longitudinally curved marginal guides and correspondingly curved interior guides arranged in line between the adjacent pairs of cutters and longitudinally curved hinged expanding members alternating with the marginal and interior guides operated with the upper cutters for expanding the meshwork as it leaves the cutters.
16. In an expanded metal machine, means for feeding stock longitudinally, upper and lower curved guides for the unslotted strips of the stock, curved expanding members hinged between the guides and means for oscillating said expanding members to open the mesh between the guides.
17. In an expanded metal machine, means for feeding stock longitudinally, upper and lower curved guides for the unslotted strips of the stock, curved expanding members hinged between the guides, means for oscillating said expanding members to open the mesh between the guides and means for vertically adjusting the guides.
18. In an expanded metal machine, a series of upper and lower cutters arranged to slit sections of a sheet and leave unslotted marginal and intermediate unslotted strips, a series of curved guides extending away from said cutters for guiding the unslotted strips and oscillating expanding members arranged between the curved guides for opening the slit portions into meshwork.
19. In an expanded metal machine, a series of upper and lower cutters arranged to slit sections of a sheet and leave unslotted marginal and intermediate unslotted strips, a series of curved guides extending upwardly away from said cutters for guiding the unslotted strips and hinged expanding members arranged between the curved guides operating intermittently for opening the slit portions into meshwork.

NORRIS ELMORE CLARK.
